UNITED STATES PATENT OFFICE

LEON A. DANCO, OF ROCKVILLE CENTER, NEW YORK, ASSIGNOR TO MCKESSON & ROBINS, INCORPORATED, OF BRIDGEPORT, CONNECTICUT, A CORPORATION OF CONNECTICUT

CONTAINER

Application filed November 9, 1928. Serial No. 318,120.

This invention relates to containers.

One object of the invention is to provide an ornamental bottle for perfume or the like mounted on a pedestal of ornamental design 5 and suitable for use as a toilet accessory.

Another object of the invention is to provide in combination an ornamental bottle for perfume or the like and an ornamental pedestal for mounting same, said bottle being provided with a depending rectangular base portion having means thereon adapted to cooperate with means on said pedestal for anchoring the base portion to the pedestal whereby the bottle and pedestal may be securely joined 15 together.

A further object of the invention is to provide in combination a pedestal and a bottle for perfume or the like mounted thereon, said pedestal having a tray member therein adapted to receive a base portion on said bottle and containing a reservoir for receiving a quantity of cementitious material with which to secure the base portion of said bottle within the tray whereby the bottle and pedestal may 25 be joined together.

A still further object of the invention is to provide an ornamental pedestal for a perfume bottle or the like of the character described adapted to be assembled at one operation.

Figure 1 is a front elevation of the container mounted on a pedestal.

Figure 2 is a vertical transverse section enlarged taken on the line 2—2 of Figure 1, looking in the direction of the arrows.

Figure 3 is an enlarged fragmentary view of the base of the container.

Figure 4 is a vertical longitudinal section of the pedestal showing a tray containing liquid cementitious material adapted to cooperate with the base portion of the bottle for securing the bottle to the pedestal.

Figure 5 is a top plan view of the pedestal, 45 and

Figure 6 is a vertical longitudinal section showing a modified form of pedestal and base portion.

The container illustrated in the drawings 50 comprises a thin bottle 1 mounted on a rec-

tangular pedestal 2 formed preferably of thin metal.

The body portion of the bottle 1 is preferably circular in form and is provided with a neck approximately of the same diameter as 55 the thickness of the bottle, and a rectangular base portion 4 having a lip or flange 5 around the bottom thereof. The flange 5 may be conveniently formed during the molding of the bottle by providing a groove 6 around the 60 sides of the base portion adjacent the bottom thereof.

The bottle 1 may be molded with the rectangular base portion 4 joined thereto and by 65 making the width of this slightly less than the width of the bottle a shoulder 4^a is provided around the bottom of the bottle whose purpose will be hereinafter explained.

The pedestal 2 on which the bottle is mounted is formed preferably in the shape 70 of a truncated pyramid with a rectangular opening 17 at the top of the frustum adapted to receive the base 4 of the bottle. The pedestal comprises a base plate 7, outer casing 8 and a tray member 9 fitted within the outer casing 8 and having sides 11 diverging outwardly from the bottom 12 so as to coincide with the sides 13 of the outer casing at its upper part and fit snugly against the same. 75 The center of the bottom 12 of the tray 9 is depressed so as to form a reservoir 14, preferably elliptical in shape, to augment the quantity of cementitious material 18 which the tray 9 is designed to hold for securing the bottle to the pedestal. The bottom 12 of the tray is depressed sufficiently so that the distended portion or reservoir rests upon the base plate 7 as at 15 and forms a support for the tray within the outer casing 8. 80

The upper edges of the outer casing are turned inwardly so as to cover the sides 11 of the tray 9 and provide a rim 16 for the shoulder 4^a on the bottom of the bottle as an assist in supporting the bottle on the pedestal. 90

In assembling the pedestal the tray 9 is inserted within the outer casing 8 and the base plate 7 placed under same. The bottom edges 10 of the sides 13 of the outer casing are then spun about the adjacent edges of 100

the base plate, securely joining all parts of the pedestal together.

In joining the bottle to the pedestal the shoulder 4^a is rested upon the rim 16 of the pedestal and the base portion 4 inserted within the opening 17. By having the opening 17 in the frustum of the pedestal conform in shape and size to the rectangular base portion 4 of the bottle 1 when the bottle is placed in position on the pedestal the base portion thereof will fit snugly within the opening 17.

Before mounting the bottle on the pedestal the tray 9 is partially filled with a cementitious material 18, such as glue, sufficient to cover the flange 5 on the bottom of the base portion 4. The flange 5 on the base portion serves to anchor the bottle within the tray when the glue solidifies over said flange and around the base of the bottle. While it is desirable that there should be a snug fit between the base of the bottle and the sides 11 of the tray 9, it is nevertheless important that sufficient clearance be left for the glue to rise and completely surround the base when set therein. By providing the reservoir 14 in the tray it is possible to use a greater quantity of glue thereby affording increased cementing strength. The glue in the reservoir becomes cemented to the bottom of the base and this may be made very effective by corrugating the base of the bottle as at 5' during the process of molding so as to afford a better cementing surface.

In the modified form of my invention illustrated in Figure 6 there is shown a container of the same general type as that illustrated in Figure 1. The bottle in this modification is preferably provided with a rectangular base 4 having a substantially square shaped tongue 19 depending therefrom, said tongue being encircled at its lower part by a flange 20. A reservoir 21 is provided in the tray 9 adapted to receive the tongue 19 and is constructed in the form of a well having downwardly diverging sides. The reservoir so constructed is narrowest at the neck thereof and therefore when the glue has hardened around the tongue 19 and flange 20 on the base of the bottle forming a solid block within the well of the reservoir this cannot be withdrawn through the narrow neck portion even though the glue should become loosened from the sides of the well and a firm anchorage for the bottle upon the pedestal is thus insured. In this modification, as well as in the embodiment first described, the glue rises within the tray when the bottle is set therein and solidifies around the base of said bottle.

While I have described what I now believe to be the best embodiments of the invention, I do not wish to be understood thereby as limiting its scope, as many changes and modifications may be made without departing

from the spirit of the invention. For example, the pedestal described is suitable for and might very well be used as a mounting for other ornamental objects of various shape and size, and all such changes and modifications I aim to include in the scope of the appended claims.

What is claimed is:

1. A container of the character described comprising in combination a bottle having a neck and body portion, a rectangular base portion depending from said body portion having a lip or flange encircling the lower part thereof and a pedestal for mounting said bottle having means thereon adapted to receive the depending base portion and to cooperate with said depending base portion and said flange whereby the bottle and pedestal may be joined together. 75

2. A container of the character described comprising in combination a bottle having a depending base portion, a lip or flange encircling the lower part of the base portion and a pedestal for mounting said bottle comprising an outer casing having an opening in the top thereof, a base plate, a tray member within said outer casing adapted to receive said base portion and a reservoir centrally disposed in said tray member for receiving a quantity of cementitious material adapted to cooperate with said base portion and flange thereon to secure said base portion within said tray member whereby the bottle and pedestal may be joined together. 80

3. A container of the character described comprising in combination a bottle having a depending base portion, corrugations on the bottom of said base portion, a lip or flange encircling the lower part of said base portion and a pedestal for mounting said bottle comprising an outer casing having an opening in the top thereof, a base plate, a tray member within said outer casing adapted to receive said base portion, and a reservoir centrally disposed in said tray member for receiving a quantity of cementitious material adapted to cooperate with said base portion, corrugations and flange thereon to secure said base portion within said tray member whereby the bottle and pedestal may be joined together. 100

4. A container of the character described comprising in combination a bottle having a depending base portion, a lip or flange encircling the lower part of said base portion, a shoulder surrounding the base of said bottle formed on the juncture of said base portion and said bottle, and a pedestal for mounting said bottle comprising a base plate, an outer casing fastened to said base plate having an opening in the top thereof, a flat rim surrounding said opening adapted to cooperate with the shoulder on the base of said bottle for supporting the bottle on the pedestal, a tray member within said outer casing adapt- 110

ed to receive the base portion of said bottle, a reservoir centrally disposed in said tray member for receiving a quantity of cementitious material adapted to cooperate with said base portion and flange thereon to secure said base portion within said tray member whereby the bottle and pedestal may be joined together.

5. A container of the character described comprising in combination a bottle having a depending base portion, a tongue extending downwardly on said base portion, a lip or flange encircling the lower part of said tongue and a pedestal for mounting said bottle having means thereon adapted to cooperate with said base portion, tongue and flange whereby the bottle and pedestal may be joined together.

6. A container of the character described comprising in combination a bottle having a rectangular depending base portion, a tongue extending downwardly on said base portion and a pedestal for mounting said bottle having a tray therein adapted to receive said base portion and tongue and cooperating therewith in joining the bottle and pedestal together.

7. A container of the character described comprising in combination a bottle having a rectangular depending base portion, a tongue extending downwardly on said base portion having a lip or flange encircling the lower part thereof and a pedestal for mounting said bottle comprising an outer casing having an opening in the top thereof, a base plate, a tray member within said outer casing adapted to receive said base portion and tongue, a reservoir centrally disposed in said tray member for receiving a quantity of cementitious material with which to secure said base portion and tongue within said tray member whereby the bottle and pedestal may be joined together.

8. A container of the character described comprising in combination a bottle having a depending base portion, a tongue extending downwardly on said base portion, a lip or flange encircling the lower part of said tongue and a pedestal for mounting said bottle comprising an outer casing having an opening in the top thereof, a base plate, a tray member within said outer casing adapted to receive said base portion and having a well centrally disposed therein for receiving the tongue on said base portion and as a reservoir for receiving a quantity of cementitious material with which to anchor said base portion and said tongue within the tray member, the distended portion of said tray member resting upon the base plate of said pedestal so as to support the tray member in position within the outer casing.

9. A container of the character described comprising in combination a bottle having a rectangular depending base portion, a tongue

extending downwardly on said base portion, a lip or flange encircling the lower part of said tongue and a pedestal for mounting said bottle in the shape of a truncated pyramid having a rectangular opening in the frustum thereof and comprising a base plate, an outer casing fastened to said base plate by spinning the lower periphery thereof about the edges of said base plate, a rectangular tray member within said outer casing secured within said casing by turning inwardly the upper edges of said casing about the upper edges of said tray, said tray member being adapted to receive the base portion of said perfume bottle and having a recessed central portion to receive the tongue on said base portion and as a reservoir for a quantity of cementitious material with which to anchor said base portion and said tongue within the tray member, the distended portion of said tray resting upon the base plate of said pedestal so as to support the tray member in position within the outer casing.

10. A container of the character described, comprising in combination a bottle, a depending base portion on said bottle, a lip or flange encircling said base portion and forming the lower peripheral edge thereof, and a pedestal for mounting said bottle having means thereon adapted to cooperate with said depending base portion and said flange whereby the bottle and pedestal may be joined together.

11. A container of the character described, comprising a bottle having a depending base portion, a lip or flange encircling said base portion and forming the lower peripheral edge thereof, and a pedestal for mounting said bottle having means thereon adapted to cooperate with said depending base portion and said flange whereby the bottle and pedestal may be joined together.

12. A container of the character described, comprising in combination a bottle, a depending base portion thereon having a portion thereof spaced from the bottom of a width less than that of the bottom thereof, and a pedestal for mounting said bottle comprising an outer casing having an opening in the top thereof, a base plate, a tray member within said outer casing adapted to receive said base portion, and a reservoir centrally disposed in said tray member for receiving a quantity of cementitious material adapted to cooperate with said base and spaced portion thereof to secure said base portion within said tray, whereby the bottle and pedestal may be joined together.

13. A container of the character described, comprising in combination a bottle, a depending base portion thereon having a portion thereof spaced from the bottom of a length less than that of the bottom thereof, and a pedestal for mounting said bottle comprising an outer casing having an opening in the top thereof, a base plate, a tray member within

said outer casing adapted to receive said base portion, and a reservoir centrally disposed in said tray member for receiving a quantity of cementitious material adapted to cooperate with said base and spaced portion thereof to secure said base portion within said tray, whereby the bottle and pedestal may be joined together.

14. A pedestal for a container or other ornamental object, comprising a base, an outer casing having upwardly extending side portions, a receptacle surrounded by said side portions adapted to receive a projecting base portion on the container or other ornamental object, and having a depressed central portion as a reservoir for cementitious material with which to secure the container or other ornamental object to the pedestal, the distended portion of said reservoir resting on said base so as to support the receptacle in position within the outer casing.

15. A pedestal for a container or other ornamental object, in the shape of a truncated pyramid having a rectangular opening in the frustum thereof, comprising a base, an outer casing having upwardly extending side portions fastened to said base at the lower edges thereof by spinning the same about said base, a rectangular receptacle surrounded by said side portions adapted to receive a projecting base portion on the container or other ornamental object and to contain cementitious material whereby to secure the container or other ornamental object to the pedestal, and a depressed central portion in said receptacle as a reservoir for such cementitious material, the distended portion of said reservoir resting on said base so as to support the receptacle in position within the outer casing.

16. A pedestal for a container or other ornamental object, comprising a base, an outer casing having upwardly extending side portions, a tray member within said outer casing and surrounded by said side portions, adapted to receive a projecting base portion on the container or other ornamental object, and having a depressed central portion as a reservoir for cementitious material with which to secure the container or other ornamental object to the pedestal.

17. A pedestal for a container or other ornamental object, comprising a base, an outer casing having upwardly extending side portions, a tray member within said outer casing and surrounded by said side portions, adapted to receive a projecting base portion on the container or other ornamental object and having a depressed central portion as a reservoir for cementitious material with which to secure the container or other ornamental object to the pedestal, the distended portion of said reservoir resting on said base so as to support the tray member in position within the outer casing and a lip on said

outer casing extending inwardly about the periphery of said tray member, so as to prevent removal of said tray member from said casing.

18. A pedestal for a container or other ornamental object, in the shape of a truncated pyramid having a rectangular opening in the frustum thereof, comprising a base, an outer casing having upwardly extending side portions fastened to said base at the lower edges thereof by spinning the same about said base, a rectangular tray member within said outer casing surrounded by said side portions adapted to receive a projecting base portion on the container or other ornamental object and to contain cementitious material whereby to secure the container or other ornamental object to the pedestal, and a depressed central portion in said tray member as a reservoir for such cementitious material, the distended portion of said reservoir resting on said base so as to support the tray member in position within the outer casing and a lip extending inwardly about the periphery of said tray member to prevent the removal thereof from said outer casing.
